UNITED STATES PATENT OFFICE.

JOHN WALKER GAY, OF CROWLEY, OREGON.

RAIL-FASTENER.

SPECIFICATION forming part of Letters Patent No. 651,526, dated June 12, 1900.

Application filed September 29, 1899. Serial No. 732,087. (No model.)

To all whom it may concern:

Be it known that I, JOHN WALKER GAY, a citizen of the United States, residing at Crowley, in the county of Polk and State of Oregon, have invented a new and useful Rail-Fastener, of which the following is a specification.

This invention relates to rail-fasteners, and includes a number of coacting devices designed to replace the ordinary spike-fastenings and overcome the numerous objections to the latter, and particularly to prevent loosening of the rails and hold them with such firmness as to completely resist spreading or dislodgment from their required gage-space, and especially on curves, and to utilize for this purpose such devices as can be easily applied and which will require but little attention after setting the same in operative position, and also of such nature as to permit an easy disconnection to remove worn-out rails and adaptable for reuse on said substitute rails.

Other objects and advantages will appear in the subjoined description and the novelty will be hereinafter claimed, the preferred embodiments of the improvement being illustrated in the accompanying drawings, wherein—

Figure 1 is a perspective view of an applied rail-fastener embodying the features of the invention. Fig. 2 is a similar view of the improved chair-bar. Fig. 3 is a similar view of one of the key-blocks. Fig. 4 is a similar view of another of the key-blocks. Fig. 5 is a section taken longitudinally of a railroad-tie and transversely of the fastening devices and rail and embodying the features of the invention as used on a straight run of track. Fig. 6 is a view similar to Fig. 1, showing the arrangement of the improved devices when adapted for use on curves. Fig. 7 is a similar view showing a slight change in the arrangement of parts. Fig. 8 is a side elevation of a tie and the improved chair-bar, showing the latter extending continuously across the tie in a longitudinal direction and which is a feature common to all the forms.

Similar numerals of reference are employed to indicate corresponding parts in the several views.

The numeral 1 designates a tie which may

be of the ordinary form of construction and is formed with a seat-recess 2 in the upper side thereof to receive a chair-bar 3. The 55 length of the recess 2 will depend upon the length of the said bar 3, and the latter extends continuously from rail to rail.

Referring now more particularly to Fig. 1, the chair-bar has cut therethrough in a transverse direction a pair of chair-slots 4, located adjacent the outer terminal of the bar and intercepted by an intermediate chair 5, having an upper horizontal face of a width equal to and adapted to receive the flange 7 of a 65 rail 8. The said slots 4 have key-grooves 5 communicating therewith and located at opposite ends of the bases thereof and in part constructed in corelative positions in the chair 3. The slots 4 and grooves 5 are adapted 70 to receive key-blocks 9, which have their outer edges relatively to the position of the rail shaped to conform to the walls of the slots 4 and grooves 5 at said points and to provide key-flanges 10 and upper bearing-flanges 11. 75 The ends of the said blocks adjacent the rail have recesses therein conforming in contour to the parts they are to fit and also to provide key-flanges 12 and holding-flanges 13, the latter having their ends extending to and 80 bearing against the web of the rail and fully contacting with the upper side of the flange of the latter. Under ordinary conditions these blocks 9 may be fitted snug enough in the slots and grooves to receive the same without other fastenings; but, as will hereinafter appear, fastenings may be used, and in some instances the opposite ends of the said blocks may be held by contiguous devices or parts of railroad attachments ordinarily employed. 85 90

The construction shown in Fig. 6 is substantially similar to that illustrated in Fig. 1, with the exception that the outside block 14 is larger than the similar block in Fig. 1 to adapt the improved fastener to curved constructions and where it is necessary to have a greater resistance established against a spreading-pressure due to a inclination of a locomotive or train, as in rounding curves.

In the arrangement shown by Fig. 6 the 100 outer terminal of the chair-bar will be thickened, as at 15, to compensate for the increase in the thickness in the block 14, or, as indicated by dotted lines, a wedge might be used

to take up the difference in thickness necessary in this arrangement of the parts of the device. It might be more beneficial in curves to have the chair-bars extend entirely across the track-bed for evident reasons, and to decrease the cost of manufacture by a saving in the use of the number of patterns it may be desirable to make all the chair-bars of an equal thickness from end to end.

10 As a safeguard against movement or displacement of the chair-bar from the tie in a transverse direction a securing-bolt 16 is to be used and projected through the said bar from end to end. This transverse movement 15 of the chair-bar in relation to the said bolt 16 is prevented by the head of the bolt extending over an adjacent portion of the tie, as shown by Fig. 1, and the nut or similar device on the opposite extremity of the bolt will 20 in like manner be projected over a portion of the tie, and these bolts being disposed in opposite extremities of the chair-bar will effectively serve to retain said bar in proper position on the tie. This same bolt 16 may at 25 times also serve to support well-known devices at opposite ends of the blocks 9 to prevent the latter from moving.

In Fig. 7 a slight change in the construction and arrangement of the several parts is 30 shown, and in this instance the tie 1 is formed with sockets 17 to receive dowel pins or studs 18 on the bottom of the chair-bar 19. The said chair-bar in this form of the device has the regular recess 20 formed in the upper portion 35 thereof, and the blocks 21 and 22 also differ in construction from those heretofore set forth. The inside blocks 21, and which will be the same on both sides of the rail in straight runs of track, have their terminals farthest from the rail fitting snugly 40 against the adjacent end wall of the said recess 20. By this means a strong reinforce is provided against the slightest movement of the rail inward toward the center of the tie. 45 The outer blocks 22 for use on curves will be formed in each instance with a flange 23 to bear upon the adjacent top portion of the chair-bar to give a better finish and also provide a reinforce-fastening. The blocks are 50 held in this arrangement by bolts 24, which have their screw-threaded ends uppermost to receive nuts 25, which are located or brought to bear firmly against the top surfaces of the said blocks, or other devices can be used for 55 this purpose.

In addition to the means set forth for preventing movement of the rails from their predetermined positions and sidewise it will be observed that the rails will also be prevented 60 from having a vertical movement, and danger arising from this form of loose play will also be avoided. The chair, as shown in Figs. 1, 2, 5, and 6, is also dispensed with in the construction shown in Fig. 7, and thus the 65 cost of manufacture will be reduced, and primarily the blocks 21 and 22, as well as the chair-bars, will all be constructed on such a

scale that when the rails are held thereby they will have the proper gage.

Either form of the improved fastener can 70 be easily set up in operative position, and when necessary the parts may be as readily disassembled by proper parties and for the purpose of track repair. The use of the improved device will avoid the accidents incident to the employment of the ordinary form of railroad-spike and will, in the main, be less expensive than the ordinary spikes, in view of the fact that they require continual replacement or tightening and the employment of a large force of operatives or track-hands to carefully look after and guard against such well-known contingencies. The ties will also be protected and their wearing qualities increased, in view of the fact that 85 they will not be subjected to the pound of a loose rail, and water will be prevented from running in under the flange and rotting the wood.

Many other advantages will appear in the 90 practical use of the device, and to accommodate various applications changes in the form, proportions, and minor details of construction may be made and substituted for those shown and described without in the least departing from the nature or spirit of the invention.

Having thus described the invention, what is claimed as new is—

1. In a rail-fastener, the combination with 100 a tie, of a chair-bar movably held thereon and extending longitudinally in a plane parallel with the tie, the lower portion of the bar and the upper part of the tie having a fixed assemblage by means completely independent of the devices, for directly holding the rails to prevent longitudinal movement of the bar toward either end of the tie and also transverse movement on the latter, the opposite extremities of the upper portion of the bar having a transverse recessed opposite end construction in a plane at a right angle to the direction of the bar and tie, rails extending transversely across the bar in the center of said recessed constructions, and 115 transversely-insertible key-blocks removably seated in the said recessed constructions on opposite sides of the rail, and having parts thereof extending over the opposite portions of the flanges of the rail, said key-blocks being wholly within the confines of and flush 120 with the opposite sides of the bar and holding the rails in central position in the recessed constructions and having the ends thereof opposite those bearing against the 125 flanges of the rails snugly abutting against the end limits or walls of the recessed constructions.

2. In a rail-fastener, the combination with 130 a tie having a recess in the upper portion thereof, of a chair-bar removably fitted in said recess, and having an upper recessed construction, a bolt extending transversely through the chair-bar and having opposite de-

5 vices thereof bearing in part upon the said bar and adjacent portions of the tie, a rail intermediately located in the said recessed construction, and key-blocks disposed in the said recessed construction on the inner and outer sides of the rails.

3. In a rail-fastener, the combination with a tie, of a chair-bar let into said tie and having upper seat-slots with inner and outer key-grooves, the said seat-slots being transversely intercepted by an intermediate chair with an upper horizontal face, and also provided with similar grooves in opposite edges, the said horizontal face of the chair being adapted to

receive the base-flange of a rail, and key-blocks disposed on opposite sides of the rail in the seat-slots and each provided with outer and inner lower key-flanges which enter the key-grooves, and also with upper bearing-flanges.

In testimony that I claim the foregoing as my own I have hereto affixed my signature in the presence of two witnesses.

JOHN WALKER GAY.
